Term of patent 14 years

(Cl. D13—1)

FIG.1

FIGURE 1 is a perspective view of a corner section of a hardboard grille embodying our new design; and FIGURE 2 is a front elevational view thereof.

It is to be understood that the pattern repeats throughout the surface area of the hardboard grille, may be of any desired size, as indicated by the dot and dash lines.

We claim:

The ornamental design for a hardboard grille, substantially as shown and described.
